(57) **CLAIM**

The ornamental design for an electronic cigarette case, as shown and described.

DESCRIPTION

FIG. 1 is a front elevational view of an electronic cigarette case;

FIG. 2 is a rear elevational view of the electronic cigarette case;

FIG. 3 is a top plan view of the electronic cigarette case;

FIG. 4 is a bottom plan view of the electronic cigarette case;

FIG. 5 is a left side elevational view of the electronic cigarette case;

FIG. 6 is a right side elevational view of the electronic cigarette case;

FIG. 7 is a first perspective view of the electronic cigarette case;

FIG. 8 is a second perspective view of the electronic cigarette case; and,

FIG. 9 is a third perspective view of the electronic cigarette case shown in an open position.

The broken lines in the drawings depict environment that forms no part of the claimed design.
